(57) **CLAIM**

The ornamental design for a cover for electronic communications device, as shown and described.

DESCRIPTION

FIG. 1 is a top left front perspective view of a first embodiment of a cover for electronic communications device showing our new design;

FIG. 2 is a front view thereof;

FIG. 3 is a rear view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is an enlarged rear view of the area in FIG. 3 indicated by the lines A and B in FIG. 3;

FIG. 9 is an enlarged top right rear perspective view of the area in FIG. 3 indicated by the lines A and B in FIG. 3;

FIG. 10 is a top left front perspective view of a second embodiment of a cover for electronic communications device showing our new design;

FIG. 11 is a front view thereof;

FIG. 12 is a rear view thereof;

FIG. 13 is a left-side elevation view thereof;

FIG. 14 is a right-side elevation view thereof;

FIG. 15 is a top plan view thereof; and,

FIG. 16 is a bottom plan view thereof.

The lines marked A and B in FIG. 3 indicate a portion of the first embodiment of the claimed design that is illustrated in enlargements and form no part of the claimed design.

The dot-dot-dash broken lines in FIGS. 8 and 9 delineate a portion of the first embodiment of the claimed design that is illustrated in enlargements and form no part of the claimed design.
